UNITED STATES PATENT OFFICE.

HARVEY L. REESE, OF PHILADELPHIA, AND HAVILAND H. PLATT, OF WALLINGFORD, PENNSYLVANIA.

INTERNAL-COMBUSTION ENGINE.

1,114,521.

Specification of Letters Patent.

Patented Oct. 20, 1914.

Application filed May 25, 1912. Serial No. 699,644.

To all whom it may concern:

Be it known that we, HARVEY L. REESE and HAVILAND H. PLATT, both citizens of the United States, residing in Philadelphia, 5 Pennsylvania, and Wallingford, Delaware county, Pennsylvania, respectively, have invented certain Improvements in Internal-Combustion Engines, of which the following is a specification.

10 One object of the invention is to provide a novel form of internal combustion engine in which the valves are operated directly from the main shaft without the use of reducing gear; it being further desired that 15 the engine shall have two or more cylinders of which the piston of one at least is employed for drawing in and compressing the fuel, while the piston of a second cylinder is employed for receiving power resulting 20 from the combustion of the fuel and for exhausting the products of the combustion.

Another object of the invention is to provide an engine having the above noted characteristics with a novel form and arrangement of cylinders and valves as hereinafter set forth.

The above noted objects we attain as hereinafter described, reference being had to the accompanying drawings, in which:

30 Figure 1, is a vertical longitudinal section of one form of an internal combustion engine constructed according to our invention, wherein our novel method of operation may be carried out, and Fig. 2, is a transverse 35 vertical section on the line *a—a*, Fig. 1.

In the above drawings, 1 represents the cylinder casting of the engine, which in the case illustrated, is equipped with two cylinders 2 and 3 having their cavities adjacent 40 each other and water jacketed in any suitable manner. Said casting 1 is mounted upon a crank case structure consisting of an upper part 4 and a lower part 5, providing bearings for a crank shaft 6. The cylinder 45 2 is provided with a removable head 7 and has slidably mounted within it a sleeve forming a cylindrical valve 8, within which is a piston 9 attached by a connecting rod 10 to one of the cranks 11 on the shaft 6. The cylinder 3 likewise has a removable 50 head 12, an internal valve sleeve 13, and a piston 14 attached through a connecting rod 15 to a second crank 16 of the shaft 6. In the case illustrated, the two cranks 11 and 55 16 are at an angle of 45° to each other, and

the valve sleeve 8 is connected through a rod 17 to an eccentric 18 on said shaft so as to reciprocate in the cylinder 2. Similarly the second valve 13 is connected through a rod 19 with an eccentric 20 on the shaft 6 so that it also is reciprocated thereby within 60 the cylinder 3. This latter is provided with an exhaust port 21, while the cylinder 2 has an inlet port 22, and there is also a transfer port 23 in the cylinder casting between said 65 two cylinders 2 and 3. The valve 8 has a port 24 capable of being brought into register with the inlet port 22 and has also a second port 25 capable of registering with the transfer port 23, while the valve 13 has 70 a port 26 also capable of registering with the transfer port, and a port 27 capable of registering with the exhaust port 21. The cylinder 3 has mounted in its head or at any other suitable point, a spark plug 28 or 75 some other suitable device for igniting fuel charges therein.

With the above described arrangement of parts, and assuming that the piston 9 is at the upper extremity of its stroke, the valve 8 is so set that its port 25 is closed, although as said piston recedes from its head, its inlet port 24 registers with the port 22 and a charge of fuel is drawn in from a carburetor or other suitable source of supply. As 85 the piston starts on its return stroke the valve 8 so moves as to close the port 24, and when the fuel charge has been compressed to about one-sixth, or any other desired fraction of its original volume, the port 25 90 is opened. At this time the piston 14 is at the upper end of its stroke and since the valve 13 is so set that its port 26 is then opened, the compressed fuel charge will pass from the cylinder 2 to the cylinder 3 as 95 the piston 9 continues to approach its head 7 and the piston 14 recedes from its head 12. This transfer of fuel is made from one cylinder to the other without resulting in substantial change in its ultimate volume or 100 pressure, and when the piston 9 reaches the upper end of its stroke, communication between the cylinders is cut off and the igniting system is so adjusted as to cause the charge in the cylinder 3 to be fired; the exhaust port 27 being closed at this time. It is, of course, obvious that the time of ignition may be advanced or retarded in the customary manner, but under working conditions we preferably adjust the parts to oper- 105 110

ate as above indicated. This combustion and expansion of gas in the cylinder 3 then forces outwardly the piston 14 and the exhaust valve port opens when said piston is 5 practically at the end of its outward stroke. Thereafter the inward movement of this piston causes the products of combustion to be expelled through the ports 27 and 21, and said ports finally close when the piston again 10 reaches the extreme inner end of its stroke. Just as said piston 14 again starts out the transfer ports of the two valves 8 and 13 are in such a position that a second charge 15 of gas, compressed in the cylinder 2 as previously described, is forced into the cylinder 3, where it is thereafter ignited and caused to exert pressure on the piston 14 as previously explained.

By the above described arrangement of 20 parts, it will be seen that the successive charges are always drawn in and compressed in the cylinder 2, and thereafter ignited, burnt and exhausted in the cylinder 3, in such manner that there is practically no contamination or dilution of the various charges 25 by products of combustion still remaining in the engine from a previous explosion. Moreover, the engine as a whole operates with certainty and the various operations 30 occur at the predetermined times calculated to secure the best efficiency of operation.

It will be noted that an engine constructed as above described is relatively simple, since the valves are operated without requiring reducing or other gearing, and the arrangement is such that the likelihood of disarrangement or excessive wear of the parts is reduced to the minimum.

It is, of course, obvious that under operating 40 conditions there is a very material alteration in the volume and pressure of the fuel during the time in which it is actually being transferred from one cylinder to the other. We preferably so arrange and adjust the 45 parts however, that just before the ignition of each charge, its volume and pressure are substantially the same as when at the beginning of its transfer from the other cylinder.

While by far the greater part of the products 50 of combustion are expelled from the cylinder 3 on the inward stroke of the piston 14, there is necessarily some slight clearance in said cylinder which prevents an absolutely complete removal of the burnt gases.

55 It is also obvious that at times in the op-

eration of the engine illustrated, the closure of the parts depends to some extent on one or both of the pistons as well as on the valves, whose ports at times register with ports in the cylinder walls when properly there 60 should be no opening. At such times the closure is performed by the piston.

We claim:—

1. The combination in an internal combustion engine, of a plurality of cylinders 65 having a transfer port between them; there being an inlet port for one cylinder and an exhaust port for the other; cylindrical sleeves respectively operative in the cylinders and each having ports of which one is 70 capable of registering with the port between the cylinders and the other is capable of registering with the second port of its cylinder; a crank shaft; a piston in each cylinder connected to said shaft; and eccentrics on the crank shaft respectively connected to the two sleeves.

2. The combination in an internal combustion engine, of a supporting structure; a crank shaft having two cranks; two cylinders adjacent each other; a piston in each cylinder connected to the crank shaft; means in one of the cylinders for igniting successive charges; there being a transfer port directly connecting the cylinders below their 85 upper ends, an inlet port for one cylinder, and an exhaust port for the other; two cylindrical valves respectively incasing the pistons of the two cylinders and provided with ports coöperating with said other ports; 90 eccentrics on the shaft; and a rod connecting each eccentric directly to one of the cylindrical valves.

3. The combination in an internal combustion engine, of a plurality of cylinders 95 having a transfer port between them; cylindrical sleeves respectively operative in the cylinders and each having a port capable of registering with the port between the cylinders; a crank shaft; and a piston in each 100 cylinder connected to said shaft.

In testimony whereof, we have signed our names to this specification in the presence of two subscribing witnesses.
